(57) **CLAIM**

The ornamental design for a child swing cushioning insert, as shown and described.

DESCRIPTION

FIG. 1 is a perspective view of a first embodiment of the design shown in its environment;

FIG. 2 is an isometric perspective view of the first embodiment of the design;

FIG. 3 is a top view of the first embodiment;

FIG. 4 is a bottom view of the first embodiment;

FIG. 5 is a front view of the first embodiment;

FIG. 6 is a rear view of the first embodiment;

FIG. 7 is a left side view of the first embodiment;

FIG. 8 is a right side view of the first embodiment;

FIG. 9 is an isometric perspective view of a second embodiment of the design in an open position;

FIG. 10 is a top view of the second embodiment in the open position;

FIG. 11 is a top view of the second embodiment in a rolled-up position; and,

FIG. 12 is a bottom view of the second embodiment in the rolled-up position.

(Continued)

The environment shown in dashed lines in FIG. 1 is not part of the claimed design.

1 Claim, 5 Drawing Sheets
